HEATING SYSTEM

Carl Georg Munters and Martin Hedmark,
Stockholm, SwedenApplication May 9, 1940, Serial No. 334,158
In Sweden July 17, 1937

8 Claims. (Cl. 237—56)

The present application is a continuation in part of our copending application Serial No. 217,698, filed July 6, 1938.

Our invention relates to heating systems for buildings, and more particularly to an improved flue or chimney forming part of such heating systems.

Heretofore it has been the practice to construct the flue or chimney of massive masonry. The thick walls of the chimney were necessary in order to provide sufficient heat insulation and the chimney necessarily had a large heat accumulating capacity, and the heat absorbed was lost to a great extent.

In accordance with our invention the flue is constructed of metallic pipe sections, which extend through the floors of the house and which are surrounded by a water jacket in the form of a shell welded or otherwise suitably secured to the section or conduit forming the flue. Said jacket forms part of a circulation system for water. One or more permanently open conduits interconnect two points of the water jacket at different levels and form a return flow conduit of said circulation system. Radiators for room heating are preferably connected to the system and adapted at will to be by-passed by or form part of said conduit or conduits. A hot water heater is in heat exchange relation with said circulation system.

A further advantage of our invention is that the flue may be installed after the building has been erected.

Another object of our invention is to provide in combination with a heating system of the above described type, an improved arrangement for heating hot water for domestic purposes.

Further objects and advantages of our invention will be apparent from the following description considered in connection with the accompanying drawing which forms a part of this specification and of which:

The single figure is a cross-sectional view of a preferred embodiment of our invention.

In the drawing there is shown a preferred embodiment of our invention installed in a house having one story and an attic above the cellar. Reference character 10 designates generally the house, having a cellar 11, a first story 12 and an attic 14 covered by a roof 15. A furnace 70 is located in the cellar 11 and includes a fuel compartment 71. The furnace is provided with water jackets 72. At the upper part of the furnace the flue gases escape through a collar 73 which carries a first flue section designated generally by reference character 74.

Section 74 includes an inner conduit 75 and an outer jacket 76. The lower end of the conduit 76 is bent inwardly, as is shown at 77 and is secured to jacket 75 in a fluid-tight manner. The upper end of the members 75, 76 are rigidly interconnected in fluid-tight manner. A conduit 78 connects the upper part of the furnace jacket 72 with the lower end of the water jacket formed in the flue section 74. A layer of insulating material 79 surrounds jacket 76.

Reference character 80 designates generally a second flue section. This section includes an inner conduit 81 for conveying products of combustion and an outer jacket 82. The upper end of jacket 82 constitutes a container 83, which concentrically surrounds part of conduit 81. The upper end of conduit 81 passes through and is rigidly connected to the upper wall 122 of container 83. The lower wall 123 of container 83 is rigidly connected to a tubular member 84 which constitutes the lower part of jacket 82. The lower ends of conduit 81 and tubular member 84 are secured together in fluid tight relationship. The flue sections 74 and 80 are secured to one another by a band 85. The upper part of jacket 76 is connected to the upper part of container 83 by means of a conduit 117 which extends through the lower wall 123 and thence upwardly within the container. A water supply pipe 87 extends through the side wall of the container 83 and is connected to the lower end of a double pipe coil 88 which is disposed within the container 83. A conduit 89 is connected to the upper end of coil 88 and extends through the side wall of container 83 and may be connected to conduits leading to taps located at various points in the house.

A conduit 90 is connected to the lower end of the container 83 and extends into the cellar 11, where it is connected through a valve 91 to a conduit 92 leading to one or more hot water radiators 93. A valve 94 may be located in the conduit 92 adjacent to the radiator in order to regulate the heat output of the radiator. A return conduit 95 leads from the bottom of the radiator to the lower part of the water jacket 72 of the furnace. A by-pass conduit 96 connects conduit 90 with conduit 95 adjacent to the lower part of the water jacket 72, while a by-pass conduit 97 connects conduit 95 with conduit 92. An overflow line 98 extends from the upper part of container 83 through the roof 15 of the house, a tank 99 being interposed in this line.

A flue section 100 is connected to the upper end of section 80 and extends through the roof.

Section 100 includes an inner conduit 101 and an outer conduit 102, an annular space 103 being formed therebetween. This may constitute a dead air space or it may be filled with heat insulating material. Insulating material 203 in block form may be placed over the upper end of section 80 and around the lower end of section 100.

A thermostatic element 104 is located in heat exchange relationship with the upper end of jacket 82 and is connected to a Bourdon tube 107. The end of this tube is connected by means of a chain 108 with a damper 109 which regulates the supply of air to the furnace 70.

The house is preferably provided with walls 110 enclosing a space within which extend the flue sections 74 and 80. A plate 111 separates said space from the cellar. A conduit 113 is provided with an air inlet opening 114 at the exterior of the building 10. This conduit leads to the lower part of a space 112 around the container 83. The upper part of the space communicates through a passage 115 with the upper part of the first story 12. This passage is provided with louvers 116. Air admitted through the conduit 113 is heated in the space 112 and discharged into the room.

The above described device operates as follows:

The fuel burning within furnace 70 heats the water contained within the water jacket 72, while the products of combustion pass upwardly through conduits 75, 81 and 101. During their passage through conduits 75 and 81 the gases heat the water contained in jackets 76 and 82, which latter jacket includes container 83. The water heated in jacket 72 around the furnace flows through conduit 78 to jacket 76 and the water flows from the upper end of this jacket through the conduit 117 into the upper part of container 83. If water is drawn from any of the taps connected to conduit 89, cold water is introduced into the coil 88 through the conduit 87. In passing through the coil 88 this water is heated, thus cooling the water contained in container 83. The water thus cooled flows downwardly through container 83 and through conduit 90. If valve 91 is closed, this water flows through by-pass 96 to conduit 95 and back to the lower part of the furnace water jacket 72. Thus, a continuous thermal circulation of water takes place through the system. It will be noted that the flow of water through coil 88 is counter-current to the flow through container 83.

If valve 91 is open, the water returning from jacket space 83 flows through this valve and through conduit 92 to the radiator 93 where it is cooled and gives up heat to the room. The water thus cooled in the radiator falls through the pipe 95 and is returned to the water jacket 72 of the furnace. The temperature at which the water within the container 83 is maintained is apt to be higher than is desirable for the temperature of the water supplied to the radiator 93. Consequently the by-pass 97 is provided whereby, if valve 91 is partially closed, a certain percentage of the water returning from the radiator 93 is recirculated and mixed with the water supply through the conduit 90 from the container 83.

The thermostatic element 104 contains a fluid, such as mercury, which expands upon an increase in temperature. This causes the Bourdon tube 107 to straighten out, thus acting through the chain 108 to close the damper 109 to thereby

reduce the amount of air admitted to the furnace. In this manner the temperature of the water within the circulating system is prevented from rising to an undesirably high value.

While we have shown and described a more or less specific embodiment of our invention, it is to be understood that this has been done for purposes of illustration only and is not to be considered as limiting the scope of the invention, which is to be determined by the appended claims.

What we claim is:

1. In a heating system, a furnace, a flue providing a path of flow for hot gas from said furnace, said flue including a plurality of hollow members joined together for flow therethrough of gas, an individual liquid jacket surrounding each of said members and said furnace, a conduit connecting adjacent jackets for flow therebetween of liquid, a heating coil disposed in the uppermost of said jackets, the conduit which connects the uppermost jacket with the jacket next below communicating with said uppermost jacket at the upper end thereof, and a conduit connecting the lower part of said uppermost jacket with the jacket surrounding said furnace.

2. In a heating system, a furnace, a flue providing a path of flow for hot gas from said furnace, said flue including a plurality of hollow members joined together for flow therethrough of gas, an individual liquid jacket surrounding each of said members and said furnace, a conduit connecting adjacent jackets for flow therebetween of liquid, the conduit which connects the uppermost of said jackets with the jacket next below communicating with said uppermost jacket adjacent to the upper end thereof, a heating coil disposed in said uppermost jacket, means for introducing water to be heated into the lower end of said coil, means to withdraw heated water from the upper end of said coil, and a conduit connecting the lower part of said uppermost jacket with the jacket surrounding said furnace.

3. In a heating system, a furnace, a flue providing a path of flow for hot gas from said furnace, said flue including a plurality of hollow members joined together for flow therethrough of gas, an individual liquid jacket surrounding each of said members and said furnace, a conduit connecting adjacent jackets for flow therebetween of liquid, the conduit which connects the uppermost of said jackets with the jacket next below communicating with said uppermost jacket adjacent to the upper end thereof, a hot water radiator, a conduit connecting the lower part of said uppermost jacket with said radiator, a conduit connecting said radiator with the jacket surrounding said furnace, a valve in the last-mentioned conduit, and a by-pass around said valve and said radiator connecting said conduits together.

4. In a heating system, a furnace, a flue providing a path of flow for hot gas from said furnace, said flue including a plurality of hollow members joined together for flow therethrough of gas, an individual liquid jacket surrounding each of said members and said furnace, a conduit connecting adjacent jackets for flow therebetween of liquid, the conduit which connects the uppermost of said jackets with the jacket next below communicating with said uppermost jacket adjacent to the upper end thereof, a hot water radiator, a conduit connecting the lower part of said uppermost jacket with said radiator,

a conduit connecting said radiator with the jacket surrounding said furnace, and a by-pass connecting said conduits whereby a portion of the water leaving said radiator is recirculated therethrough.

5. In a heating system for buildings having a plurality of floors, a furnace, a flue providing a path of flow for hot gas from said furnace, said flue including a hollow member for flow therethrough of gas, liquid jacket means surrounding said member and said furnace, said jacket means extending upwardly through said floors and forming part of a circulation system for liquid, a permanently open conduit interconnecting two points of the liquid space of said jacket means at different levels and forming a return flow conduit of said circulation system, a radiator for room heating connected to said conduit, means for by-passing fluid around said radiator, and a hot water heater in heat exchange relation with said jacket means.

6. In a heating system, a furnace, a flue providing a path of flow for hot flue gases from said furnace, a liquid jacket surrounding at least a portion of said flue, conduit means connected at different levels to said jacket to provide a liquid circulation system, said conduit means including an inlet connected to the upper part of said jacket and an outlet connected to the lower part of the jacket, a water heater in heat exchange relation with the upper part of

said jacket, and means for supplying relatively cold water to said heater to thereby produce a downwardly directed flow of liquid in said jacket in a direction counter-current to the flow of said flue gases.

7. In a heating system, a furnace, means forming a flue for products of combustion from said furnace, vertically disposed upper, intermediate and lower liquid jackets surrounding said flue, the upper part of the lower jacket being connected with the lower part of the intermediate jacket, the upper part of the intermediate jacket being connected with the upper part of the upper jacket, the lower part of the upper jacket being connected with the lower part of the lower jacket, and a water heater in heat exchange relation with the upper jacket.

8. In a heating system, a furnace, a flue providing a path of flow for hot flue gases from said furnace, a liquid jacket surrounding at least a portion of said flue, a radiator, a conduit connected to an upper portion of said jacket and to said radiator, said conduit having an intermediate portion located below said radiator, a return conduit connected to said radiator and to a lower portion of said jacket, and a by-pass conduit connected between the low intermediate portion of the first-mentioned conduit and said return conduit.
